COMBINATION LOCK

Philip G. Coleman, Chattanooga, Tenn., assignor, by direct and mesne assignments, of two-fifths to Edward L. Klapper, one-fifth to Andrew A. Wassick, and two-fifths to Lela H. Coleman, all of Chattanooga, Tenn.

Application June 30, 1948, Serial No. 36,029

2 Claims. (Cl. 70—312)

1

My invention relates to a combination lock and more particularly pertains to a lock of such a nature that the elements, of which it is composed, must be adjusted into a predetermined position to each other before the lock is effective.

The principal object of my invention is to provide a lock, of simple and inexpensive construction, which may be affixed to the lid of a container, and which requires that the parts of the lock be placed in a predetermined position to each other before the lid can be unlocked by removing the locking element from a keeper on the container.

A further object of my invention is to provide a lock having a plurality of rotatable members which may be repositioned in annular indicating members to change the combination of the lock.

A further object of my invention is to provide a lock which is particularly useful for containers such as jewel cases, coin boxes, luggage or the like which have relatively thin walls.

Further objects, and objects relating to details of construction and economies of operation, will definitely appear from the detailed description to follow. In one instance, I have accomplished the objects of my invention by the devices and means described in the following specification. My invention is clearly defined and pointed out in the appended claims.

Combination locks constituting preferred embodiments of my invention are illustrated in the accompanying drawings, forming a part of this specification, in which:

Fig. 1 is a plan view of a container with the combination lock.

Fig. 2 is a sectional view taken along the line 2—2 of Fig. 1.

Fig. 3 is a partial, sectional view of the substance of Fig. 2 but showing the lid in raised position.

Fig. 4 is a detail, sectional view taken along the line 4—4 of Fig. 2.

Fig. 5 is a detail, sectional view taken along the line 5—5 of Fig. 3.

Fig. 6 is a perspective view of the bushing used in the lock.

Fig. 7 is a view of a modified form of the rotatable dials of my invention.

Fig. 8 is a perspective view of the shiftable pin used in the lock.

Fig. 9 is a plan view of a form of my invention showing the lock in latching position.

Fig. 10 is a view of the substance of Fig. 9 with the lock in the disengaged position.

Fig. 11 is a detail, sectional view taken along the line 11—11 of Fig. 10.

2

Fig. 12 is a detail, sectional view taken along the line 12—12 of Fig. 10.

Fig. 13 is a detail view of the movable locking member.

5 In the drawings, the same reference numerals refer to the same parts throughout the several views and the sectional views are taken looking in the direction of the arrows at the ends of the section lines.

10 10 In general, my invention consists of a lock which has a plurality of members rotatable about a common axis, each of the members having a hole and a radial slot therein. In the holes in the rotatable members I may provide a bushing having a slot. A pin, rectangular in cross-section extends through the slot in the bushing and is shiftable into the radial slots in the rotatable members when said slots are in alignment. The pin extending through said slots has secured to 15 one end a flat latch member which is shiftable to locking engagement with a keeper on the container. When this pin occupies the slot in the bushing, the turnable members are independently rotatable about the pin and bushing, but, when 20 the pin is shifted into the ends of the slots in the turnable members, the shifting of the pin also causes the latch member to be moved to interlocking engagement with a slot on the lid of the container so the parts are held against relative rotation when the lid is unlocked. Since 25 the lock members must be adjusted into predetermined relation with each other before the pin can be shifted to unlock the latch member, it is desirable to indicate the relative positions of the turnable members. This may be done by providing 30 various markings on the members to be aligned in a certain relation before the pin can be shifted from neutral to effective position.

35 The pin member may be provided with a knob which covers the slotted opening. The pin preferably has a flat stem which moves in the slot to move the locking piece, but is long enough when shifted to position to release the latch member, to prevent rotation of the dials until the latch member is moved back into locking position. I 40 have also shown a modification wherein the rotatable members are provided with irregularly shaped peripheries and matching annular members having their inner surfaces shaped to correspond to the irregular shapes on said rotatable members. This provides for changing the combination of the lock by merely repositioning the annular members on their respective turnable members.

45 50 I have also shown a form of my invention particularly useful for luggage locks. In this form 55

Fig. 12 is a detail, sectional view taken along the line 11—11 of Fig. 10.

I provide a forked spring which projects into a keeper. When it is desired to lock the spring in the keeper, a latch member is moved between the prongs of the forked spring to press them outwardly into locking engagement with the keeper.

Referring to the numbered parts of the drawings, I have shown, in Fig. 1, a box 10 having side walls 11, 12, 13 and 14 and a curved bottom 15. A lid 16 is hinged to the container on pins 17 and

18. The lid 16 has an opening 20 in which bushing 22 is rotatable. A turnable disc 21 is rotatable on the bushing 22 and a smaller rotatable disc 23 is superimposed on disc 21 and is also rotatable on the bushing 22. Each of the discs, 21 and 23 are provided with a slot 26 which when the dials are in selected positions form with the slot 26' in the lid 16, a composite radial slot.

A pin 27, having a head or knob 28, on one end adapted to cover the slot in the member 23, is normally positioned in a slot 24 in the bushing 22 and may be shifted, by moving the knob, when the slots 26 and 26' are aligned. The bottom end of the pin 27 has a flat locking member 41 secured thereto which is movable into and out of locking engagement with a keeper 42 provided on one of the side walls 14. The head of the pin may be made large enough to form an operating handle or knob and to cover the slot 26 in disc 23 completely.

When the discs are in a predetermined position the slots on each disc are aligned with the slot in the lid so that the pin may be shifted to cause the latch member to be moved.

The embodiment of my invention just described constitutes a simple form of lock that is operable by positioning the rotatable discs 21 and 23 and the knob 28 to predetermined positions, and by shifting the pin to cause the latch member to be moved.

Since it is necessary to adjust or position the discs 21 and 23 and the head 28 relative to each other, to bring the slots into alignment it is desirable to indicate the relative positioning of said members. To that end, I mark the characters such as diamonds or hearts 40 on the knob 28. I mark letters of the alphabet such as indicated at 42a, on the disc 23, and on the disc 21, I mark letters such as indicated at 43, which may be in alphabetical order. On the lid 16 I mark characters such as 44.

The relative positions of the dial members may be indicated by these markings. Thus, as illustrated, when the letter "B" on dial 21, the letter "O" on dial 23 and the letter "Y" on the lid 16 are in line with the diamond the turnable members 21 and 23 are so positioned that the slots 26 are in alignment with the slot 26', so that the pin 27 can be shifted from its central position to unlock the locking member. In other words, the combination indicating the positioning of the parts, which permits the pin to be shifted and allows the latch member to be moved, is diamond followed by "BOY."

In Fig. 7 I have shown an embodiment of my invention wherein turnable discs such as 30 and 31 are provided which have holes 36 and 37 and radial slots 28a and are mounted on bushing 22. The peripheries of discs 30 and 31 have projections which fit into corresponding recesses 32 and 33 provided on annular members 34 and 35. The bushing 22 has a slot 24 through which a pin 27 extends and is movable when the discs are brought to the proper predetermined position in the same manner as shown in the preferred form of my in-

vention. The two piece rotatable member construction permits the user to change the combination of the lock by changing the position of the slots relative to markings on the dials, by repositioning the discs such as 30 and 31 with respect to annular members 33 and 34.

In Figs. 9 and 13, I have shown a modified form of my invention which is particularly useful for locks for luggage.

This form comprises a plate member 50, which has mounted thereon a plurality of disc members such as 51 and 51a rotatable about a common axis, each of the members having a hole and a radial slot 52 therein. In the hole, a bushing 53 is provided having a slot 54. A headed pin 55 extends through the slot 54 in the bushing 53 and is shiftable therein when said slots are aligned. The headed pin has a latch piece 56 secured to one end and is shiftable to a locking position. Lying on each side of the piece 56 are container locking spring members 57 and 58 between which the locking member may move, said locking member being shaped in a manner such that it expands the spring members when the headed pin 55 and the locking member is shifted. I provide a keeper member 60 which has an opening 61 to receive the forked spring ends 62 and 63 of container locking spring members 57 and 58. To lock the two members together, the ends 62 and 63 are positioned in the opening 61 and expanded by movement of latch piece 56 to the position as shown in Fig. 9. This causes the ends 62 and 63 to be secured in the keeper member. I provide means on the disc members 51 and 51a which must be aligned before the latch piece can be moved. These markings can be of any suitable character, for example such as are shown in the dials in the preferred form of my invention.

It will be evident that my invention constitutes a relatively inexpensive and simple locking device, suitable for use on containers, such as coin boxes, jewel boxes, luggage or the like having relatively thin walls, and which will prevent access to such containers by unauthorized persons, but which can quickly be set by an authorized person, who knows the combination, to such position that the container may be opened.

I am aware that the structures illustrated herein, as embodiments of my invention, are susceptible of considerable variation without departing from the spirit of my invention and, therefore, I claim my invention broadly as indicated in the appended claims.

Having thus described my invention, what I claim as new and useful, and desire to secure by Letters Patent, is:

1. In a container having a cover with a hole and a communicating radial slot and a side wall with a keeper member, a combination lock comprising the combination of a plurality of superimposed rotatable members having a common axis, each being formed with a hole and a communicating radial slot, a pin extending through the hole in said members and through the hole in said cover, a knob on the outer end of said pin for shifting said pin radially of said members and said cover when the slots are aligned, and a locking member on the inner end of said pin and shiftable therewith to locking engagement with the keeper member for locking the container.

2. In a container having a cover with a hole and a communicating slot therethrough and a side wall provided with a keeper element, a combination lock comprising a cylindrical bushing having a radial slot therethrough rotatable in

said hole in the cover, a plurality of turnable members rotatably mounted on said bushing, a pin arranged in said radial slot in said bushing and shiftable into said slot in the cover of said container, said turnable members being formed with slots extending radially from said bushing for receiving said pin when said slots are aligned with each other and with the slot in said cover, a knob on the outer end of said pin, and a locking member on the inner end of said pin for engaging or disengaging said keeper when said pin is shifted radially of said turnable members.

PHILIP G. COLEMAN.
